United States Patent

Des. 235,757
Patented July 8, 1975

235,757

TIRE

Jean-Pierre Largeau, Boulogne, France, assignor to
Pneumatiques Caoutchouc Manufacture et Plastiques
Kleber-Colombes

Filed Apr. 13, 1973, Ser. No. 350,999

Claims priority, application France Feb. 8, 1973

Term of patent 14 years

Int. Cl. D12—15

U.S. Cl. D12—143

FIG. 1

FIG. 2

FIG. 1 is a perspective view of a tire embodying my new design, it being understood that the tread pattern is repeated throughout the circumference of the tire, the opposite side being substantially the same as that shown herein; and

FIG. 2 is an enlarged fragmentary developmental plan view of the tread pattern shown in FIG. 1.

I claim:

The ornamental design for a tire, substantially as shown and described.
